*Fig. 6**Fig. 7**Fig. 8*

FIG. 1 is a perspective view of an etcher cabinet in accordance with our invention;

FIG. 2 is a front elevational view of the cabinet shown in FIG. 1;

FIG. 3 is a right side view of the cabinet shown in FIG. 2;

FIG. 4 is a top view of the cabinet shown in FIG. 2;

FIG. 5 is a rear view of the cabinet shown in FIG. 2;

FIG. 6 is a top view of an etcher cabinet, showing a modified form thereof;

FIG. 7 is a right side view of the cabinet shown in FIG. 6;

FIG. 8 is a rear view of the cabinet shown in FIG. 6.

The left side of the cabinet shown in FIG. 2 is a mirror image of the illustration of FIG. 3.

The front view of the cabinet shown in FIG. 7 is generally the same as the front view of the cabinet shown in FIG. 2.

The left side of the cabinet shown in FIG. 6 is a mirror image of the illustration of FIG. 7.

The broken portion of the illustration of FIG. 6 is a drafting expedient only.

This is a continuation-in-part of our copending application Ser. No. 194,798, filed Nov. 1, 1971, now abandoned.

We claim:

The ornamental design for etcher cabinets, as shown and described.
